GAME CABINET

Kenneth W. Sauter, Morgan Hill, Calif., assignor to Atari, Inc.

Filed June 26, 1975, Ser. No. 590,687

Term of patent 14 years

Int. Cl. D21—01

U.S. Cl. D34—5 J

FIG. 4

FIG. 2   FIG. 1   FIG. 3

FIG. 1 is a side elevational view of a game cabinet embodying my new design, both sides being the same.

FIG. 2 is a rear view of the game cabinet shown in FIG. 1.

FIG. 3 is a front elevation view of the game cabinet shown in FIG. 1.

FIG. 4 is a top plan view of the game cabinet shown in FIG. 1.

The bottom of the game cabinet is generally a planar surface, and the left side is a mirror image of the right side.

I claim:

The ornamental design for a game cabinet, as shown and described.
